UNITED STATES PATENT OFFICE.

ARTHUR F. JACOBSON, OF DETROIT, MICHIGAN.

PERMUTATION LOCK.

1,427,106.

Specification of Letters Patent. Patented Aug. 29, 1922.

Application filed June 10, 1921. Serial No. 476,378.

To all whom it may concern:

Be it known that I, ARTHUR F. JACOBSON, a citizen of the United States, residing at Detroit, in the county of Wayne and State 5 of Michigan, have invented certain new and useful Improvements in Permutation Locks, of which the following is a specification.

This invention relates to permutation locks, and has for its object a permutation 10 lock provided with a knob which is a piece separate from the spindle and the numeral disk. This knob is connected with the spindle and numeral disk by a concealed but fragile connection.

15 A great many safes are opened by the so-called yeggmen or safe-breakers simply by striking the knob with a suitable tool until the numeral disk and spindle are knocked off the door, giving access to the notched 20 disks inside. This permits the safe-breaker to line up the notches in the disk to permit the tumblers to drop in, the bolts shot, and the safe opened. Even if the yegg does not gain access to the safe he very often 25 jimmies the lock mechanism so as to require a new lock or so that the safe cannot be opened except by an expert.

It is the object of the present invention 30 to provide a construction which will permit the knob to be easily broken off even with the face of the numeral disk so that the yeggman is frustrated in his attempt to pry the disk and the spindle out or to injure the inner mechanism of the lock.

35 In the drawings,—

Fig. 1 is a front elevation of the lock.

Fig. 2 is a fragmentary section showing 40 only the numeral disk and a part of the spindle together with the knob and the fragile connection.

a designates the ordinary numeral disk that is used on a safe. *b* is the knob. The face of this disk *a* at the center is provided with a nicely machined portion to receive 45 the knob *b* which has its corresponding face nicely machined to fit tightly onto a similar surface of the numeral disk. The numeral disk is bored and tapped at its center, as is also the knob. However, the knob is only 50 bored part way in from the rear face and the numeral disk only part way in from the front face. This permits a fragile threaded stud *c* to be turned into the knob and then the stud turned into the threads 55 of the numeral disk or the knob turned onto

the threads of the stud if the stud has been first located in the numeral disk. This stud is provided with a weakened portion or a portion of reduced diameter *x* arranged to come at the dividing line of the 60 knob and numeral disk. The knob may then be turned down very tightly on the numeral disk. There is also provided some means for locking the knob from turning off from the threaded stud. I find that a 65 very convenient and blind way of locking the knob to the numeral disk is to provide a plurality of small sockets *d* in the numeral disk and provide a single pin perforation *e* in the base of the knob. The knob 70 can be turned down tightly to bring the pin perforation in registry with one of these sockets *d*. A pin *f* may then be driven in and filed or finished off on the top so it is practically unseen. This forms a lock to 75 prevent the knob from backing off the stud.

The stud is made of some highly fragile metal, such as some of the hardened steels that have very little resistance to a fracture. There are numerous alloys or metals 80 that can be used to provide a suitable stud which at the same time will be easily fractured when the knob is subjected to a heavy blow.

It will be obvious when a safe-breaker 85 strikes the knob with a heavy blow that the knob will separate from the disk, the stud breaking in two at the reduced portion *x* and thereby leaving the numeral disk and the inner mechanism unharmed. The 90 knob having been broken off at the dividing line of the knob and disk, there will be no surface left for the safe-breaker to apply a tool and pry the disk out and thereby the attempt to get at the inner mechanism of 95 the lock will be frustrated. Furthermore, no hole will be left in the numeral disk in which a charge of explosive may be sealed by beeswax or the like to shatter the lock, when exploded.

100 In the claims the disk is spoken of as the numeral disk as a descriptive designation. Obviously the numerals might be on the ring in which the disk revolves and the disk would not then be strictly a numeral disk 105 but I want it understood that such a disk would come within my invention.

What I claim is:

110 1. In a permutation lock, a numeral disk provided with a tapped central opening and

a knob provided with a tapped central opening at its back, and a threaded fragile stud for holding the knob to the numeral disk.

2. In a permutation lock, the combination of a numeral disk, a knob separate from the numeral disk, and a fragile stud for securing the numeral disk and the knob together, same fragile stud let into the knob from the rear and concealed at the front of 10 the knob.

3. In a permutation lock, the combination of a numeral disk, a knob separately formed, a threaded stud for securing the knob to the numeral disk, said numeral disk 15 being provided with a plurality of pin sockets and the said base of the knob provided with a pin perforation which can be caused to register with one of the pin sockets when the knob has been turned down tightly 20 upon the threaded stud, and a pin in the registering perforation and socket for locking the knob from rotation to prevent the

knob from backing off from the threaded stud.

4. In a permutation lock, the combination of a numeral disk, a knob separate therefrom, and a stud for connecting the two and provided with a weakened portion which will allow the stud to fracture on the division line between knob and numeral disk 25 30 when subjected to unusual stress.

5. In a permutation lock, the combination of a numeral disk of metal, a metal knob separate therefrom, and a stud constructed of hard, fragile steel for connecting the two 35 and provided with a reduced weakened portion near the face of the disk which will allow the stud to fracture on the division line between knob and numeral disk when subjected to unusual stress. 40

In testimony whereof I affix my signature.

ARTHUR F. JACOBSON.
